CLAIM

I claim the ornamental design for a clip for a multi-purpose tool, as shown and described.

DESCRIPTION

FIG. 1 is an elevated perspective view of a clip for a multi-purpose tool showing my new design.

FIG. 2 is an elevated perspective view of the clip of FIG. 1, attached to a multi-purpose tool;

FIG. 3 is a right side view of the clip of FIG. 1;

FIG. 4 is a left side view of the clip of FIG. 1;

FIG. 5 is a top view of the clip of FIG. 1;

FIG. 6 is a bottom view of the clip of FIG. 1;

FIG. 7 is a back view of the clip of FIG. 1; and,

FIG. 8 is a front view of the clip of FIG. 1.

The broken lines in FIG. 2 showing a multi-purpose tool are for the purpose of illustrating environmental structure and form no part of the claimed design.
